UNITED STATES PATENT OFFICE.

CONYERS BUTTON, OF PHILADELPHIA, PENNSYLVANIA.

DESIGN FOR SCARF.

Specification forming part of Design No. **6,673**, dated May 27, 1873; application filed May 13, 1873.

To all whom it may concern:

Be it known that I, CONYERS BUTTON, of Philadelphia, Pennsylvania, have invented a Design for a Scarf, of which the following is a specification:

The figure in the accompanying drawing clearly represents my design for a scarf, the remainder of the pattern being merely a repetition of that which appears.

The scarf has a narrow central stripe, A, of the character represented, a narrow zigzag mottled stripe, B, at each side of and adjacent to the central stripe, and a wide stripe, D, at each edge, this latter stripe being the principal feature of the design. The central portion of the stripe D is occupied by foliated ornamenta-

tion, consisting of a continuous stem and leaves, and at each edge of the said stripe is a narrow border, a, of the character clearly represented in the drawing.

Irrespective of the colors employed, I claim—

The design for a scarf, substantially as described, and as represented in and by the accompanying drawing.

In testimony whereof I have signed my name to this specification in the presence of two subscribing witnesses.
